COMBINED SCRAPER AND HAMMER

William E. Holt, Oakland, Calif.

Application February 1, 1949, Serial No. 601

Term of patent 14 years

(Cl. D54—13)

To all whom it may concern:

Be it known that I, William E. Holt, a citizen of the United States, residing at Oakland, in the county of Alameda and State of California, have invented a new, original, and ornamental Design for a Combined Scraper and Hammer, of which the following is a specification, reference being had to the accompanying drawing, forming part thereof.

Fig. 1 is a side elevation of a combined scraper and hammer, showing my new design;

Fig. 2 is a front end view;

Fig. 3 is a rear end view, partly in section; and

Fig. 4 is a plan view.

I claim:

The ornamental design for a combined scraper and hammer, as shown.

WILLIAM E. HOLT.
